COMBINED ROCKET AND LAUNCHING VEHICLE TOY

John W. Ryan, Bel Air, and Daniel H. Meggs, Redondo
Beach, Calif., assignors to Mattel, Inc., a corporation
of California

Filed Feb. 1, 1966, Ser. No. 826

Term of patent 14 years

(Cl. D34—15)

FIG. 3

FIG. 4

FIG. 1 is a perspective view of a combined rocket and launching vehicle toy, showing our new design;

FIG. 2 is a top plan view of the design;

FIG. 3 is a right-hand side elevational view of the design, being the side opposite that shown in FIG. 1; and

FIG. 4 is a front end elevational view taken from the right as seen in FIG. 3.

We claim:

The ornamental design for a combined rocket and launching vehicle toy, as shown.
